UNITED STATES PATENT OFFICE.

THOMAS F. JENNINGS, OF GARFIELD, UTAH.

FLASK.

1,322,022.

Specification of Letters Patent.

Patented Nov. 18, 1919.

Application filed May 15, 1918. Serial No. 234,612.

To all whom it may concern:

Be it known that I, THOMAS F. JENNINGS, a citizen of the United States, residing at Garfield, in the county of Salt Lake and

5 State of Utah, have invented certain new and useful Improvements in Flasks, of which the following is a specification.

This invention relates to an improvement in flasks, and has for its principal object to 10 provide an improved flask in which integral or fixed cross bars are dispensed with, and bars are used which may be quickly and readily removed or inserted. My invention generally pertains to the cope, and it may 15 be used in conjunction with the drag if so desired.

In the drawings—

Figure 1 is a plan view of one form of my invention;

20 Fig. 2 is an end elevation of the same;

Fig. 3 is an end elevation, a portion thereof being shown in section;

Fig. 4 is a perspective of one of the locking wedges;

25 Fig. 5 is a perspective detail of one of the bar sockets;

Fig. 6 is a plan view of a detail of a modified form of my invention; and

30 Fig. 7 is a view similar to Fig. 3 of the construction shown in Fig. 6.

Like numerals refer to like elements throughout the drawing. 10 indicates generally the flask frame provided with trunnions 10^a, or the like, as is customary in 35 foundry practice. Located on opposite inner faces of a pair of ends of the frame 10 are the sockets generally indicated by 11, see Fig. 5, for example, consisting of a vertical rib 11^a having an overhanging top lug 40 or portion 11^b, a bottom portion 11^c, and an inclined rib 11^d. Removable cross bars of metal or the like, indicated by numeral 12, extend across between corresponding socket members 11. In placing the bars they are 45 inclined sufficiently to clear the top lugs portion 11^b and dropped into the sockets, after which locking wedges 13, shown in Fig. 4, are driven home, as shown in Fig. 3, for example, locking the bars in position beneath the lugs portion 11^b, thereby preventing 50 their accidental displacement.

The function of these bars is to hold the sand against dropping during molding or casting, and the same are generally used 55 with a cope as is well known, although it is obvious that my invention may be applied to the drag if it becomes advisable.

In present day constructions the bars are formed integral with the flask frame, or are bolted or riveted in place, as a result of 60 which it is impossible to readily remove them for use in other flasks or for replacement, and they transmit strains, due to expansion or contraction, to the frame. My invention overcomes this objection, and enables the use of the flask at shorter intervals. 65

In Figs. 6 and 7 I have shown a modified form in which the top lugs 11^b of the sockets is dispensed with, the construction in other respects being the same. This construction 70 is preferable for use in making steel castings, for example, or in other processes where it is advisable to bake the mold prior to casting. In this latter construction, the bars may be removed by direct lift without 75 having to slant them for lifting. It will be obvious that where the bars are made a part of the mold it will be possible to remove the entire mold from the flask frame by the use of the form shown in Figs. 6 and 7 to permit 80 the use of such frame with other bars, thereby reducing the number of flasks required where various styles of castings are made. 85

It will be obvious that my invention is susceptible of modification and improvement, and I do not wish to be restricted to the form shown and described except as defined in the appended claims.

What I claim is:

1. In combination, a flask comprising an 90 integral metal frame having integrally projecting ribs on the inner walls thereof forming sockets closed at the bottom, and removable metal bars fitting at their extremities in said sockets.

2. In combination, a flask comprising an integral metal frame having integrally projecting ribs on the inner walls thereof forming sockets closed at the bottom, removable metal bars fitting at their extremities in said 100 sockets, and locking members fitting in said sockets and coacting therewith to lock said bars in place.

3. In combination, a flask comprising an integral metal frame having integrally projecting ribs on the inner walls thereof forming sockets closed at the bottom, lugs projecting partially over said sockets, movable metal bars fitting at their extremities in said 105 sockets, and means to lock said bars in said 110 sockets beneath said lugs.

In testimony whereof, I have subscribed my name.

THOMAS F. JENNINGS.
